NELSON H. HENDERSON AND HIRAM L. HENDERSON, OF SYRACUSE, NEW YORK.

DRY KILN.

1,422,202.

Specification of Letters Patent. Patented July 11, 1922.

Application filed May 14, 1921. Serial No. 469,601.

To all whom it may concern:

Be it known that we, NELSON H. HENDERSON and HIRAM L. HENDERSON, citizens of the United States, and residents of Syracuse, in the county of Onondaga and State of New York, have invented a certain new and useful Dry Kiln, of which the following is a specification.

This invention relates to dry kilns of the 10 class used for drying lumber and other wood products, coats of paint, varnish etc. on articles as the so-called siccative coatings, enamel on leather etc., and has for its object construction and means for effecting and 15 controlling the circulation of the atmosphere of the kiln and the taking in and humidifying of outer air and also the recirculating of the atmosphere in the kiln, which kiln is particularly simple in construction and 20 especially economical to operate.

The invention consists in the novel features and in the combinations and constructions and relative arrangement of the controlling means hereinafter set forth and 25 claimed.

In describing this invention, reference is had to the accompanying drawings in which like characters designate corresponding parts in all the views.

30 Figure 1 is a fragmentary plan view of a kiln embodying our invention.

Figure 2 is a fragmentary sectional view.

This kiln comprises generally, a drying room and a heating chamber below the drying room in communication therewith, and 35 a steam injector arranged to circulate the atmosphere in the kiln and to maintain the humidity of the atmosphere and also to draw in, humidify and circulate outside air and to create a draft in the stacks.

1 designates the kiln which consists of the usual enclosing walls. 2 is the drying room. 3 is the heating chamber below the central portion of the drying room and communicating therewith, the drying room being 40 separated from the chamber 3 merely by suitable supports as beams 4 for supporting rails 5 for the trucks 6 which carry the lumber or other material to be dried. The 45 kiln here shown is formed double and has stacks 8 on opposite sides thereof. The kiln in keeping with the double construction is also provided with a recirculating chamber 9 located on opposite sides of the chamber 50 3 and communicating with the side portions of the drying room 2. The stacks 8 com-

municate at 10 with the lower portions of the chambers 9. The partitions 11 which separate the chambers 9 from the chamber 3 are formed with automatically operated 60 means as dampers 12 which swing inwardly into the chamber 3 to automatically control the circulation from the chambers 9 to the chamber 3. When the pressure in the circulating chambers 9 is greater than that in 65 the heating chamber 3 the dampers 12 will open inwardly by the pressure and a portion of the atmosphere which would otherwise pass out through the stacks, passes the dampers 12 into the chamber 3 and is re- 70 circulated through the drying room.

As here illustrated, the kiln is provided with air ducts 14 extending along its bottom transversely thereof from the sides and formed with outlets 15 into the circulating 75 chamber 3 and also with inlets 16 into the chambers 9, these ducts also communicating with the inlets 17 for the outside air. Said ducts 14 extend from each side of the kiln toward the other side and those projecting 80 from one side terminate short of the other side and alternate with those projecting from such other side. Any desired number of ducts may be used.

18 are steam blowers or injectors connected to a suitable source of steam supply through pipes as 19, an injector 18 being located in each duct between the inlets 16, 17 and the outlets 15 to draw outside air from the air intake 17 and also recirculate 90 the atmosphere entering through the inlets 16 from the chambers 9. As here shown, the injector is located adjacent each air intake and suitable means as a damper 20 is provided in each duct for controlling the 95 flow of air from the air inlet 17 and also for controlling the recirculation of air from the chamber 9 through the inlet 16.

When this damper cuts off more or less the inlet of air from the air inlet 17, it 100 correspondingly opens more or less the recirculating passage 16.

21 are dampers in the openings 10 connecting the chamber 9 and the stacks for controlling the flow through the stack and 105 regulating the pressure in the chambers 9.

22 are heating coils located in the chamber 3 and connected to a suitable source of steam supply. Steam pipes extend longitudinally at intervals into the chamber 3 110 as the pipe 23 which has discharge openings 24 for discharging steam into the kiln when

necessary to obtain the desired humidity in addition to that supplied by the injectors.

The injector pipes 19, supply pipes for the steam coils and for the steam jets 24 5 are provided with a suitable manually operated valve not shown, and also the kiln is provided with suitable wet and dry bulb thermometers to guide the operator in opening and closing the dampers, the injectors 10 and steam pipes.

In operation, the steam projected from the injectors 18 passes through the ducts 14 out through the outlets 15, past the heating coils 22 by which it is heated, and circulates 15 upwardly through the drying room to the top thereof where the current of atmosphere is divided into two currents by the baffle plate 26, which currents pass laterally and downwardly along the sides of the drying 20 room and kiln into the chambers 9 and out through the stacks.

Part of the atmosphere may be again recirculated by passing the dampers 12 which 25 automatically operate when the pressure in the chamber 3 is less than that in the chambers 9. Also by closing the dampers 21 of the stacks the pressure in the chambers 9 can be raised so as to cause recirculation 30 past the valves or dampers 12. By operating the damper 20 to partly or wholly close the air inlet 17, a partial or nearly complete recirculation is effected by means of the injector 18 from the chambers 9 through inlet 35 passages 16 of the ducts 14. By opening the dampers 21 more or less the draft in the stacks can be increased or diminished to suit requirements. Additional steam when required, can be taken in through the pipe 23.

Owing to the use of the injectors a positive circulation is maintained in the kiln 40 and also in the stacks and the medium used to maintain the circulation also supplies the moisture for effecting the drying of the lumber or coatings, hence the injector performs 45 the functions of maintaining the circulation, humidifying the atmosphere and creating the draft in the stacks. Hence, this kiln is more economical in operation than when fans and other mechanical blowers for circulating the atmosphere are employed or 50 when the draft is maintained in the stacks by the use of additional coils or draft producing devices in the stacks.

What we claim is:

- 55 1. A dry kiln having an air inlet and a steam injector arranged to draw the air in through the inlet into the kiln, substantially as and for the purpose described.
- 60 2. A dry kiln having a passage provided with an outside air inlet and discharge outlets into the kiln, and a steam blower between such inlet and the outlets, substantially as and for the purpose specified.
- 65 3. A dry kiln provided with a passage having an inlet in the kiln and an outlet to

the kiln, and a steam injector arranged in the passage between the inlet and the outlet to maintain circulation of the atmosphere in the kiln and to supply moisture to such atmosphere, substantially as and for the purpose set forth. 70

4. A dry kiln having a circulating passage having an inlet into the interior of the kiln, an air inlet communicating with the circulating passage and with the outside of 75 the kiln, and an outlet into the kiln, and a steam blower arranged in the circulating passage between said inlets and said outlet in position to recirculate the atmosphere of the kiln and also draw in air through the air inlet and humidify the same, substantially as and for the purpose described.

5. A dry kiln having a circulating passage having an inlet into the interior of the kiln, an air inlet communicating with the 85 circulating passage and with the outside of the kiln, and an outlet into the kiln, and a steam blower arranged in the circulating passage between said inlets and said outlet in position to recirculate the atmosphere of the 90 kiln and also draw in air through the inlet, and means for controlling the flow through such inlets, substantially as and for the purpose specified.

6. A dry kiln having a passage provided 95 with an outside air inlet and discharge outlet into the kiln, a steam blower between such inlet and the outlet, and means for controlling the flow of air through the inlet, substantially as and for the purpose de- 100 scribed.

7. A dry kiln provided with a passage having an inlet in the kiln and an outlet to the kiln, and a steam injector arranged in the passage between the inlet and the outlet 105 to maintain circulation of the atmosphere in the kiln and to supply moisture to such atmosphere, and means for controlling the flow through the inlet, substantially as and for the purpose set forth. 110

8. In a dry kiln, a recirculating passage, a steam injector arranged in the passage and operating to maintain the circulation of the atmosphere in the kiln, and means for controlling the recirculation of the atmosphere 115 by the injector, substantially as and for the purpose specified.

9. In a dry kiln, a circulating passage extending along the bottom of the chamber and having openings in its top into the interior 120 of the kiln, and a steam injector arranged in said passage, substantially as and for the purpose set forth.

10. In a dry kiln, a passage along the bottom of the kiln and having outlets in its top 125 into the interior of the kiln, and also having an inlet at one end into the kiln, and a steam injector arranged in the passage between the inlet and the outlet, substantially as and for the purpose described. 130

11. A dry kiln having a passage extending along the bottom of the kiln and provided with outlets in the top wall into the kiln, an air inlet communicating with such passage at one end, and a steam injector located in the passage between the air inlet and the outlets, substantially as and for the purpose specified.

12. In a dry kiln, a passage extending along the bottom of the kiln and having outlets in the top wall into the kiln, and an air inlet communicating with such passage at one end, and a steam injector located in the passage between the inlet and the outlet, and means for controlling the flow of air from the inlet into the passage, substantially as and for the purpose set forth.

13. In a dry kiln, ducts extending transversely from each side of the kiln toward the other side, the ducts extending from one side alternating with those projecting from the other, and the ducts having outlets in their upper sides into the kiln, a steam injector located in each duct in position to force air through the ducts and the outlets thereof and circulating the same in the kiln, substantially as and for the purpose described.

14. In a dry kiln, ducts extending transversely from each side of the kiln toward the other side, the ducts extending from one side alternating with those projecting from the other and the ducts having outlets in their upper sides into the kiln, each duct having an inlet leading from the interior kiln near the side of the kiln from which the duct projects, and a steam injector located in each duct between the inlet and the outlet thereof for circulating the atmosphere through the ducts upwardly through the kiln and downwardly along the sides of the kiln and into the ducts, substantially as and for the purpose specified.

15. A dry kiln having a drying room in the upper portion thereof and a heating chamber below the central part of the drying room and circulating chambers at opposite sides of the former chamber, such chambers opening into the bottom of the drying room, automatic pressure operated dampers in the partitions between the circulating chambers and the heating chamber, chimneys communicating with the circulating chambers, and means for circulating the atmosphere upwardly through the heating chamber, the drying room, downwardly along the sides of the kiln into the circulating chambers, substantially as and for the purpose set forth.

16. A dry kiln having a drying room in the upper portion thereof and a heating chamber below the central part of the drying room and circulating chambers at opposite sides of the former chamber, such chambers opening into the bottom of the drying room, automatic pressure operated dampers in the

partitions between the circulating chambers and the heating chamber, chimneys communicating with the circulating chambers, and a steam blower arranged to circulate the atmosphere in the kiln and supply moisture thereto, substantially as and for the purpose described.

17. A dry kiln having a drying room in the upper portion thereof, a heating chamber below the central part of the drying room and circulating chambers at opposite sides of the former chamber, such chambers opening into the bottom of the drying room, automatic pressure operated dampers in the partitions between the circulating chambers and the heating chamber, chimneys communicating with the circulating chambers, an air duct having outlets into the heating chamber, and having an inlet for outside air, and a steam injector in the duct between the air inlet and the outlet of the duct, substantially as and for the purpose specified.

18. A dry kiln having a drying room in the upper portion thereof, and a heating chamber below the central part of the drying room and circulating chambers at opposite sides of the former chamber, such chambers opening into the bottom of the drying room, automatic pressure operated dampers in the partitions between the circulating chambers and the heating chamber, chimneys communicating with the circulating chambers, air ducts communicating respectively with the circulating chambers, and with the outside air and having outlets into the heating chamber, and a steam injector in the ducts between the inlets and outlets thereof, substantially as for the purpose set forth.

19. A dry kiln having a drying room in the upper portion thereof, and a heating chamber below the central part of the drying room and circulating chambers at opposite sides of the former chamber, such chambers opening into the bottom of the drying room, automatic pressure operated dampers in the partitions between the circulating chambers and the heating chamber, chimneys communicating with the circulating chambers, air ducts communicating respectively with the circulating chambers and with the outside air and having outlets into the heating chamber, and a steam injector in the ducts between the inlets and outlets thereof, and means for controlling the flow through the inlets of the ducts, and means for controlling the flow through the chimneys, substantially as and for the purpose described.

20. A dry kiln having a drying room in the upper part thereof, a heating chamber below the central part of the drying room and recirculating chambers below opposite sides of the drying room and at opposite sides of the circulating chamber, partitions separating the chambers, depending inwardly swinging dampers in said partition,

stacks communicating with the lower portions of the recirculating chambers, and means in the kiln for circulating the atmosphere therein, substantially as and for the purpose specified.

21. A dry kiln having a drying room in the upper part thereof, a heating chamber below the central part of the drying room and recirculating chambers below opposite sides of the drying room and at opposite sides of the circulating chamber, partitions separating the chambers, inwardly swinging dampers in said partition, stacks communicating with the lower portions of the recirculating chambers, and a steam injector arranged to force atmosphere upwardly through the circulating chamber, the drying room and downwardly along the sides of the kiln into the recirculating chambers, substantially as and for the purpose set forth.

22. In a drying kiln having a drying room in the upper portion thereof, a heating chamber below the central portion of the drying room and opening at its top into the drying room, circulating chambers below the side portions of the drying room and at opposite sides of the former chamber, inwardly swinging dampers in the partitions separating said chambers, ducts extending horizontally along the bottom of the kiln and having outlet openings into the heating chamber and also having inlets communicating with the circulating chambers, and a steam injector located in the ducts, substantially as and for the purpose described.

23. In a dry kiln having a drying room in the upper portion thereof, a heating chamber below the central portion of the drying room and opening into the drying room, additional chambers below the side portions of the drying room and at opposite sides of the former chambers, inwardly swinging dampers in the partition separating said chambers, ducts extending horizontally along the bottom of the kiln and having outlet openings into the former chamber and also having inlets communicating respectively with the additional chambers, outside air inlets opening into the ducts, means for controlling the flow of the atmosphere from the circulating chambers into the duct and for controlling the flow of 55 outside air in the duct, and a steam injector

arranged in the ducts between the inlets and outlets thereof, substantially as and for the purpose specified.

24. In a dry kiln having an air inlet, and a steam injector arranged to draw the air 60 into the intake, circulate it in the kiln and supply moisture thereto, substantially as and for the purpose described.

25. A dry kiln, an air intake and recirculating passages and a steam injector arranged to draw the air through the intake and through the recirculating passage and to circulate the atmosphere in the kiln, substantially as and for the purpose specified.

26. In a dry kiln, a steam injector arranged to circulate the atmosphere of the kiln and supply additional moisture thereto, substantially as and for the purpose set forth.

27. A dry kiln having a stack and a steam blower arranged in the kiln and arranged to circulate the atmosphere from the kiln and through the stack, substantially as and for the purpose described.

28. A dry kiln having a receiving chamber and a recirculating chamber, a steam blower arranged to force the air through the first mentioned chamber and through the kiln and into the recirculating chamber, and means for automatically establishing communication between the recirculating chamber and the first mentioned chamber, substantially as and for the purpose specified.

29. A dry kiln having an outlet and an air inlet, and a circulating passage and a steam blower arranged to draw the air through the air inlet and effect a circulation thereof through the kiln and through the outlet, and means for controlling the outlet whereby the atmosphere of the kiln is recirculated by the steam blower, substantially as and for the purpose set forth.

30. In a dry kiln having an air inlet, a steam blower arranged to draw the air through an inlet and circulate the same 100 through the kiln, and means for supplying additional steam to the air in the kiln, substantially as and for the purpose described.

In testimony whereof, we have hereunto signed our names, at Syracuse, in the county 105 of Onondaga, and State of New York, this 20th day of April, 1921.

NELSON H. HENDERSON.
HIRAM L. HENDERSON.
